Patented Jan. 13, 1920.

FIG. 1

FIG. 2

FIG. 4

FIG. 3

FIG. 5

Inventor
Charles H. Parmelee

By Attorney
Frank Warren

UNITED STATES PATENT OFFICE.

CHARLES H. PARMELEE, OF SEATTLE, WASHINGTON, ASSIGNOR, BY MESNE ASSIGNMENTS, TO PACIFIC RADIATOR SHIELD CO., OF SEATTLE, WASHINGTON, A CORPORATION.

RADIATOR-SHIELD.

1,327,877.

Specification of Letters Patent. Patented Jan. 13, 1920.

Application filed April 2, 1918. Serial No. 226,309.

To all whom it may concern:

Be it known that I, CHARLES H. PARMELEE, citizen of the United States, residing at Seattle, in the county of King and State of Washington, have invented a certain new and useful Improvement in Radiator-Shields, of which the following is a specification.

My invention relates to improvements in radiator shields and the object of my invention is to provide a radiator shield for radiators of that class which is used for heating rooms of buildings by steam or hot water, which radiator shield shall be made of such materials and be of such form as will adapt it to be so removably attached to a radiator disposed near the wall of a room that the adjacent portion of said wall shall be protected from excessive radiant heat and from the deposit of dust, which, without the presence of said radiator shield, would be deposited on said wall from ascending currents of heated air; and a further object of my invention is to provide a radiator shield some of whose parts shall be adapted to contain a quantity of water which by its evaporation will increase to a desired degree the humidity of the air of the room heated.

I accomplish these objects by devices illustrated in the accompanying drawings, where-

30 in—
Figure 1 is a perspective view of a radiator to which is attached a radiator shield embodying my invention;

Fig. 2 is an enlarged view of my said 35 radiator shield in elevation of its inner side;

Fig. 3 is a view of the shield looking vertically upward from a point directly beneath it;

Fig. 4 is a view of the shield in vertical 40 cross-section on broken line 4, 4 of Fig. 2; and

Fig. 5 is a perspective view of a detail of the shield.

Referring to the drawings, throughout 45 which like reference numerals indicate like parts, a piece of sheet metal, of a width a little greater than the length of the radiator, (as the radiator 6, to which is to be attached a shield), is bent to form a vertical rearward portion 7 that is rectangular in area, a forwardly inclined integral portion 8, whose front edge portion 9 is rolled under into the form of a segment of a tube, and an in-

tegral bottom portion 10 which may be bent 55 as required to extend rearwardly to any angle that may cause its bottom edge to make contact with the adjacent wall 11 of a room to be heated, as shown more clearly in Fig. 4, to thereby prevent dust laden air 60 from flowing upwardly between the back surface of the vertical rearward portion 7 and said wall 11, to thus prevent dust from being deposited on said wall 11.

Fastened by bolts, as bolts 12, to each of 65 the opposite end edges of the several integral portions 7, 8 and 9, is an angular flange, as flanges 13 and 14 respectively, of the form shown.

The entire area of the inner side surface 70 of the vertical rearward portion 7 is covered by a lining 15 of non-heat-conducting material, as sheet asbestos, which is secured in its position by the nuts of some of the bolts 12 as shown more clearly in Fig. 4, 75 which lining 15 shields the portion 7 from the radiant heat of the adjacent radiator 6.

Fastened against the under surface of the forwardly inclined portion 8, by a bolt 16 and two of the bolts 12, is a bar 17 of channel iron which is disposed at a distance from the front edge portion 9 so as to extend throughout the distance between the flanges 13 and 14, to thus stiffen the portion 8 and to make it inflexible.

Rigidly attached to each of the end portions of the bar 17 so as to extend vertically downward therefrom is one of two supporting brackets, as supporting brackets 18 and 19, each of which is adapted by its position 90 to engage with and rest upon the top end of a different one of the sections of the radiator 6 to sustain the entire weight of the shield.

Extending through each of the opposite 95 end portions of the vertical rearward portion 7 and through a portion of the adjoining one of the flanges 13 and 14, at a point about midway between the portions 8 and 10, is a clamping hook, as clamping hooks 20 and 21, which clamping hooks 20 and 21 are each provided with a screw-threaded shank and a clamping nut like the shank 22 and nut 23 of the clamping hook 20 shown in Fig. 4 where by they may be adjusted each to hook 100 on to a section of the radiator 6 to clamp the shield thereto as shown in Fig. 1 where the

clamping hook 21 engages with an end section of the radiator 6.

Fastened to the under side of the portion 8 in a position between the bar 17 and the 5 upper part of the portion 7 is a container 24 for water which container 24 is shown by a perspective view in Fig. 5 and whose rearward and front vertical walls 25 and 26 respectively have portions of their top 10 edges cut out, as indicated in Figs. 4 and 5, to form passageways for air so that currents of heated air may flow through said container 24 and over the surface of the water therein contained, to evaporate said water 15 and humidify said current of air which, thus humidified, flows outwardly under the front edge portion 9 into the room heated.

The portion 8 is provided with a hole 27 disposed directly above the central portion 20 of the container 24, through which hole 27 water may be poured into said container 24, said hole 27 being indicated by a dotted circular line in Fig. 3.

Manifestly, changes may be made in the 25 form, dimensions and arrangement of parts of my invention without departing from the spirit thereof.

What I claim is:

1. A radiator shield having integral sheet metal top and back portions, a transversely arranged reinforcing channel bar rigidly fastened to said top portion against the under face thereof, and twisted sheet metal brackets for supporting said shield rigidly secured within the channel of said reinforcing bar and depending from the latter to rest transversely upon the sections of a radiator, substantially as described. 30

2. A radiator shield including a shield member having top and back walls, forwardly extending horizontal clamping hooks having shanks adjustably connected to said back wall and having their free hooked ends horizontally arranged to engage the end sections of a radiator to fasten the 40 shield member to the radiator, and sheet metal supporting brackets rigidly secured to and depending from said top wall, said brackets having their free ends resting transversely upon the top of the radiator 50 sections, substantially as described.

In witness whereof, I hereunto subscribe my name this 27th day of March, A. D. 1918.

CHARLES H. PARMELEE.
